PHOTOELECTRIC SYSTEM

Daniel J. Mindheim, Glen Cove, N. Y., assignor to Lindly & Company, Inc., Nassau County, N. Y., a corporation of New York

Application July 16, 1956, Serial No. 598,088

6 Claims. (Cl. 250—219)

The present invention relates to a photomultiplier system and is directed particularly to obtaining uniform signals from such systems despite varying conditions during operation.

Photomultipliers are useful in many applications where it is desired to convert a visual or light signal into an electrical signal. An example of such use is in apparatus for inspecting textile yarns and other materials forming the subject matter of a United States patent application filed by Howard C. Lindemann and Daniel J. Mindheim on July 17, 1956, Serial Number 598,364. In such apparatus the material to be inspected passes through a light beam directed between a light source and the phototube, a suitable optical system being provided to define the beam and direct it on the cathode of the tube. An interruption or sudden variation in the light received by the phototube produces a signal pulse which is amplified and used to actuate any desired mechanism, for example to stop the material and/or to provide a visual, audible, electrical or other signal as desired.

However, the use of photomultipliers has heretofore been limited by the fact that their operation is not sufficiently uniform and stable under conditions encountered in use to give satisfactory results. For example, in the above mentioned yarn inspecting apparatus, the amount of light impinging on the cathode of the phototube may be decreased by dirt or lint collecting on the envelopes of the lamp and the phototube and on the lenses or other elements of the optical system. The light may also be varied by variations in the voltage supply of the lamp and by deterioration of the lamp in use. Moreover, changes occur in the characteristics of the phototube itself due, for example, to changes in temperature or to the progressive decay of the tube. Because of these factors affecting their operation, photomultipliers have not heretofore been sufficiently stable for many applications where they might otherwise be useful.

It is an object of the invention to provide a photomultiplier system that is highly sensitive and is nevertheless highly stable in the sense that under all operating conditions it will produce a constant signal pulse for a constant light interruption. The system in accordance with the invention is thus capable of achieving uniform results over a long period of time with minimum maintenance and attention despite variation in operating conditions such as changes in temperature, deterioration of the phototube or light source and collection of dirt on the envelopes of the phototube and lamp and on elements of the optical system. As applied to yarn inspecting apparatus, the system in accordance with the invention also makes it possible to inspect yarns of different sizes without modifying the equipment. Such apparatus using a photomultiplier system in accordance with the present invention adjusts itself automatically to accommodate yarns of different sizes without affecting the selected value of the signal pulse produced by a given defect in the yarn.

Other objects and advantages of the invention will

appear from the following description and claims in conjunction with the accompanying drawings which illustrate by way of example one embodiment of the invention and in which:

Figs. 1 and 2 are together a wiring diagram of a photomultiplier and control system in accordance with the invention.

Fig. 3 is a wiring diagram of an amplifier for amplifying the signal of the photomultiplier, and

Fig. 4 is a schematic plan of yarn inspecting apparatus utilizing a photomultiplier system in accordance with the invention.

The embodiment of the invention illustrated by way of example in the drawings comprises a phototube 1, a lamp 2 arranged to direct a beam of light on the phototube, a main power supply unit 3, a second power supply unit 4 to the supply power to the lamp, a control circuit 5 for controlling the light output of the lamp in accordance with the output of the phototube and an amplifier 6 (Fig. 3) for amplifying a signal from the phototube for use in controlling equipment or in operating a visual, audible or electrical signal. To illustrate one of many applications of invention there is shown schematically in Fig. 4, an arrangement for inspecting a sheet of yarns. In the arrangement shown, a beam of light from the lamp 2 is directed on the phototube 1 by a suitable optical system 7 which has been indicated schematically as lenses, though it will be understood that suitable optical elements are used to define a beam of the desired characteristics, for example a beam of parallel rays. The material M that is to be inspected is shown as a plurality of yarns which are supplied for example from individual spools or cones and are wound onto a rotating reel 8. In passing from the supply to the reel 8, the yarns pass over and under suitable guide bars 9 which guide the yarns so that they pass across the beam of light directed by the lamp and optical system 7 onto the phototube 1. As long as the yarns are free from defects, they intercept a constant amount of light so that the output of the phototube 1 has a predetermined steady value. However, any projecting portions of fibers on the yarns will intercept more light and thereby momentarily change the output of the phototube to produce a signal which is suitably amplified by the amplifying circuit 6 and used for example to stop the reel 8 or to produce a visual, audible or other signal.

In order to be used in applications such as that described above, the phototube must be extremely sensitive. However, this gives rise to the difficulty that the correct functioning of the tube may be impaired by lint, dust or dirt collecting on the envelope of the phototube 1 or lamp 2 or on elements of the optical system 7. Moreover, the phototube is affected by other factors such as temperature variation and progressive aging of the tube and of the lamp. In accordance with the invention, these difficulties are overcome by controlling the light output of the lamp so that the normal or steady output of the phototube is maintained at a predetermined optimum value.

The phototube 1 is a photomultiplier having a cathode 11, anode 12 and a plurality of dynodes 13. The cathode 11 is connected by a suitable lead 14 to terminal A of a plug 15 through which a high negative voltage, for example minus 590 volts, is supplied to the cathode from the power supply circuit described below. The dynodes 13 are connected to the lead 14 through a series of resistances 15 in the manner shown (Fig. 2) so that the negative voltages applied to the dynodes are successively of lower value. In the operation of the tube, electrons emitted by the cathode when light strikes it are directed to the first dynode where they produce more electrons by secondary emission. These electrons are directed to

the second dynode and produce a still larger number of electrons which are directed to the third dynode. This is continued through the entire series of dynodes. The dynodes thus have the effect of multiplying the emission of the cathode so as to obtain a much higher current value than would otherwise be obtained. The phototube 1 is provided with a shield 16 connected through a high resistance 17 to the lead 14. The shield is provided with a suitable window for transmission of light from the lamp to the phototube.

The anode 12 of the photomultiplier tube 1 is connected through a condenser 18 to the grid of a triode 20A, the plate of which is connected by a lead 21 to terminal E of plug 15 through which B+ voltage is applied to the plate. The cathode of the triode 20A is connected by a lead 22 to an output plug 23. The anode 12 of the phototube 1 is also connected by a lead 24 through a resistance 25 and microammeter 26 to ground or other reference point of predetermined potential. It will be understood that the current flowing through the resistance 25 will be dependent on the amount of light falling on the cathode of the phototube as well as on other factors such as temperature, extent of deterioration of the tube, etc. The condenser 18 blocks the flow of steady current from the anode 12 of the phototube to the grid of the triode 20A. However, when there is a sudden change in current produced for example for momentary interruption of light from the condenser 18 to the grid of tube 20A which acts as a cathode follower to transmit an amplified pulse to the output 23.

The power supply 3 (Fig. 1) operates from a suitable source, for example 110 volt A. C. mains 30, and supplies regulated voltages of constant value to the several components of the equipment as required. The power supply circuit is shown as comprising a transformer 31, the primary of which is connected through a switch 32 with the supply mains 30. The secondary of the transformer is provided with a plurality of taps to furnish the various voltages that are required. Leads 33 are connected to terminals C and D of plug 15 and provide 6.3 volt current to heaters for various tubes. Leads 34 supply 6 volt current to the heaters of tubes 37 and 38. A circuit comprising transformer secondary leads 35 and 35a, tubes 37 and 38 and a series of gas filled diodes 39 with connections and associated components as shown in the drawings supplies a high negative voltage to terminal A of the plug 15 which, as described above, is connected to the cathode of the phototube 1. A further circuit comprising transformer secondary leads 40, tubes 36, 41 and 42 and gas-filled diodes 43 with the connections and associated components shown in the drawings supply a positive voltage of constant value, for example 250 volts, to the lamp control circuit 5 as will be described below.

The lamp 2 (Fig. 2) is shown as an incandescent lamp having a filament 45, one end of which is connected by a lead 46 to ground while the other end is connected by a lead 47 to the lamp power supply 4. The power supply 4 is shown as an oscillator supplying radio frequency current to the lamp 2. It comprises a tetrode 50 and an oscillator coil 51 having windings 51a, 51b and 51c. One end of the winding 51c is grounded while the other is connected by lead 47 to the filament 45 of lamp 2. One end of the winding 51a is connected by lead 52 to the cathode of tube 50. The other is connected through lead 53 and through a resistance 54 and condenser 55, arranged in parallel with one another, to a grid of tube 50. A condenser 56 is connected in parallel across the winding 51a. One end of the winding 51b is connected by lead 52 to the cathode of tube 50 while the other end is grounded and is connected through a lead 57 and condenser 58 to the other grid of tube 50. The heater of

tube 50 is connected by leads 33 to a source of current and also connected through condensers 59 to ground. The anode of the tube 50 and the last mentioned grid are connected by a lead 60 to terminal G of the plug 5 15 through which they are connected to the circuit 5 for controlling the intensity of the lamp 2, as described below.

The lamp control circuit comprises the resistance 25 (Fig. 2) and a triode 20B, the grid of which is connected through resistances 61 and 62 to the anode 12 of phototube 1. The grid is also connected through resistances 61 and 63 to ground. As the cathode of tube 20B is connected to ground, it is in effect in parallel with the resistance 25 so that the voltage between the grid and cathode of tube 20B depends on the IR drop in resistance 25 and hence on the steady current of the phototube 1. The anode of tube 20B is connected through a plate resistance 64 and lead 21 to terminal E of plug 15 supplying B+ voltage and is connected by a lead 65 to terminal B of plug 15. This terminal is connected by a lead 65a (Fig. 1) through a resistance 66 to the grid of a triode 67. The grid is also connected through a condenser 68 to ground. A selected positive voltage is supplied to the cathode of the triode 67 by a potentiometer 69 connected to a lead 70 to which a constant positive voltage, for example 250 volts, is supplied by the power supply circuit described above. The anode of tube 67 is connected by a lead 71 to the control grid of a tetrode 72, which grid is also connected through a resistance 73 to the positive voltage supply lead 70. The anode of tube 72 is connected to one of the leads 40 of the transformer 31 while the other lead is connected through a leakage resistance 73 to the second grid of the tube. The cathode of tube 72 is connected by a lead 60a to terminal G of the plug 15 and hence to the anode of tube 50 (Fig. 2) of the oscillator supplying current to the lamp 2.

In the control circuit, triodes 20B and 67 act as D. C. amplifiers to amplify the voltage appearing across the resistance 25 by reason of the IR drop resulting from the steady current output of the phototube 1 while the tetrode 72 acts as a variable resistance controlling the supply of power from the oscillator circuit 4 to the lamp. If, for any reason, the anode of the phototube tends to draw less current, the voltage at the anode will rise, i. e. become less negative, due to the decrease in IR drop across the resistance 25. The potential of the grid of tube 20B will thereupon tend to rise, causing an increase of current through the plate resistor 64. This results in an increase in the IR drop across the plate resistance 64 and a lowering of the plate voltage of the tube 20B. This lower voltage is transmitted directly to the grid of tube 67 (Fig. 1) causing a decrease in the current flow through the resistance 73 through which the plate is connected to the constant regulated voltage supply lead 70. The decrease in current from the regulated voltage supply to the plate of tube 67 results in an increased potential on said plate. This potential is directly transmitted to the grid of tube 72, lowering the resistance of this tube and raising the voltage supplied to the oscillator circuit 4 through leads 60 and 60a. The R. F. output of the oscillator to the lamp 2 is thereby increased with a resulting increase in the light output of the lamp. Thus a decrease in the current of phototube 1 results automatically in increasing the light output of the lamp 2 which in turn increases the current of the phototube 1 to bring it back to the selected level. The potentiometer 69 provides for initial adjustment of the lamp 2 at the desired value. The top limit for the lamp is controlled by the cut-off point of the tube 67.

The output terminal 23 of the phototube circuit is connected as desired to an external circuit to which it is desired to transmit a signal pulse resulting from momentary interruption or diminution of light falling on the phototube, for example by reason of a defect in

material being inspected. As illustrated by way of example in Fig. 3, the output plug 23 is connected through a mating plug 23' and a potentiometer 75 to an amplifier 6 comprising tubes 81, 82, 83 and 84 together with the associated components and connections shown in the drawings. The output of the amplifier circuit controls a relay 85 having operating contacts 86 and 87. As illustrated in the drawing, the contact 86 controls an output 88 adapted to be connected to any device which it is desired to control, for example a stop-motion for the reel 8 of the inspecting mechanism shown by way of example in Fig. 4. The contact 87 is shown connected to a counter 89 to record the number of operations. It will be understood that the amplified output of the phototube 1 may be used to operate signal or any other device as desired. The output circuit comprising the cathode follower 20A and the amplifier 6 is responsive to signal pulses emitted by the phototube by reason of a momentary interruption or diminution of light falling on its cathode. The light control circuit, on the other hand, acts as an integrating circuit, the effect of pulses being damped out by the circuitry shown and particularly by the condenser 68 in the grid circuit of the control tube 67. Hence the light control circuit is not responsive to signal pulses but rather to the steady or integrated current output of the phototube 1. The light output of the lamp 2 is thereby automatically and precisely controlled to maintain the steady current output of the phototube at a constant value.

By reason of the extreme sensitivity required in order for the apparatus to respond to a single filament or fibre, the available margin between electrical noise in the circuit and a signal pulse is extremely small. The light control circuit in accordance with the invention makes it possible to operate in this small margin despite deterioration of the phototube or lamp or other factors such as the optical system becoming dirty. Satisfactory operation of the apparatus over a long period of time is thereby assured.

While a preferred embodiment of the invention has been shown in the drawings and particularly described the invention is in no way limited to this embodiment but is susceptible of modification and variation within the scope of the appended claims.

What I claim and desire to secure by Letters Patent is:

1. In apparatus for inspecting material, a sensitive photoresponsive element, the electrical conduction of which varies with small variations in the amount of light falling on said element, means for supplying a constant direct current potential, a primary circuit comprising said photoresponsive element and potential supplying means connected to supply a constant potential to said element, an electrical lamp, means directing light from said lamp onto said photoresponsive element to induce a flow of current through said element, said current decreasing with a decrease of light on said element, means for passing material to be inspected through the path of said light so that a momentary variation in said material causes a variation in the light received by said photoresponsive element and a corresponding variation in the current flowing through said element to produce a signal pulse, an output circuit responsive to pulses, means connecting said photoresponsive element to said output circuit to transmit a signal pulse to said output

circuit, means supplying current to said lamp, and a light control circuit for varying the current supplied to said lamp and thereby controlling the light emitted by said lamp, said light control circuit comprising an integrating circuit connected to said primary circuit, said integrating circuit being responsive to steady current flowing through said photoresponsive element but not responsive to signal pulses and means controlled by said light control circuit to increase the current supplied to said lamp upon decrease of the steady current flowing through said photoresponsive element to maintain the current of said element at a constant value except for said signal pulses.

2. Apparatus according to claim 1, in which said output circuit is reactively coupled with said primary circuit.

3. Apparatus according to claim 1, in which said primary circuit comprises a resistance connected in series with said photoresponsive element and said potential supply means and in which said light control circuit is connected across said resistance.

4. In apparatus for inspecting material, a photomultiplier tube having a cathode, anode and a series of dynodes, power supply means for maintaining a constant potential difference between said cathode and anode and lesser potential differences between successive dynodes of said series, an electric lamp having a light output varying with current supplied to said lamp, means directing light from said lamp onto said tube to excite said tube and thereby produce a flow of current through said tube, said current decreasing with a decrease of light falling on said tube, means for passing material to be inspected through the path of said light so that a momentary variation in said material causes a variation in the light received by said phototube and a corresponding variation in the current flowing through said phototube to produce a signal pulse, an output circuit responsive to pulses, means coupling said phototube to said output circuit to transmit a signal pulse to said circuit, means supplying current to said lamp, and a light control circuit for varying the current supplied to said lamp, said light control circuit comprising an integrating circuit connected to said phototube, said integrating circuit being responsive to steady current flowing through said phototube but not responsive to signal pulses and current varying means controlled by said light control circuit to increase the current supplied to said lamp upon decrease of the steady current through said phototube to maintain the current through said phototube at a constant value except for said signal pulses.

5. Apparatus according to claim 4, in which said means supplying current to said lamp comprises a radio frequency oscillator having its output connected to said lamp.

6. Apparatus according to claim 4, in which said current varying means comprises a variable resistance tube having a grid connected to said light control circuit.
